OTHER PUBLICATIONS

Advertisement by Land O' Lakes showing a personal size container for beverages, trademarked as the "Grip." It also has a resealable top, (ad shows date of 2000).

Primary Examiner—Carol Rademaker

(74) Attorney, Agent, or Firm—Colin P. Cahoon; Carstens & Cahoon, LLP

CLAIM

The ornamental design for a snack food container, as shown and described.

DESCRIPTION

FIG. 1 is a perspective view of the snack food container of the present invention;

FIG. 2 is a front elevation view of the snack food container of the present invention, with the rear elevation view, left elevation view, and right elevation view all mirror images of the front elevation view;

FIG. 3 is a top plan view of the snack food container of the present invention; and,

FIG. 4 is a bottom plan view of the snack food container of the present invention.

The broken line shown on the bottom in FIG. 4 defines the boundary of the claim. The central portion within this broken line boundary forms no part of the claimed design.
